UNITED STATES PATENT OFFICE.

JOSEPH WRIGHTSMAN, OF HARPER, KANSAS.

WINDOW-SHUTTER.

SPECIFICATION forming part of Letters Patent No. 277,971, dated May 22, 1883.

Application filed January 11, 1883. (No model.)

To all whom it may concern:

Be it known that I, JOSEPH WRIGHTSMAN, a citizen of the United States, residing at Harper, in the county of Harper and State of Kansas, have invented a new and useful Window-Shutter, of which the following is a specification, reference being had to the accompanying drawings.

This invention relates to window-shutters and mechanism for operating the same; and it consists in certain improvements in the construction and arrangement of parts, which will be hereinafter fully described, and particularly pointed out in the claims.

15 In the drawings hereto annexed, Figure 1 is a front view of a window-frame embodying my improvements. Fig. 2 is a rear view of the same. Fig. 3 is a horizontal sectional view on the line $\alpha\alpha$ in Fig. 1. Fig. 4 is a vertical sectional view on the line yy in Figs. 1 and 2. Fig. 5 is a vertical sectional view on the line zz in Fig. 1. Fig. 6 is a vertical sectional view on the line vv in Figs. 1 and 2, and Fig. 7 is a detail view of the catch or fastening for 25 the outside shutter.

The same letters refer to the same parts in all the figures.

A in the drawings designates the window-frame, which is constructed with a box or casing, C, at the top, and with pockets or recesses B B at the sides, which may serve to accommodate the sash-weights, as the mechanism to be herein described will not interfere in the least with the operation of said weights.

35 D is a roller journaled in the sides of the box or casing C, transversely over the window-frame, and provided with a pulley, E, at one end. To the said roller are attached two flexible straps, F F, which may be of leather, 40 thin steel, or any other suitable material which shall be sufficiently strong and durable for the purpose intended. To the said flexible straps are bolted or otherwise secured transverse slats G G, of steel or iron, which form the 45 shutter or blind. Other material than steel or iron may of course be used in the construction; but I prefer the materials named, as being light, durable, and practically burglar-proof.

50 The sides of the pockets or recesses B are provided with slots H H, into which the ends of the slats G project, thus rendering the dis-

placement of the shutter impossible. The bottom of the casing C likewise has a slot, I, for the passage of the slats when they are being wound upon or unwound from the roller.

At the lower end of the shutter is secured an angle-plate or slat, J, which, when the roller is being wound, serves to prevent the end of the shutter from passing through the slot I, 60 which said slot is completely closed by the said angle-plate, thereby obviating drafts.

At the upper end of the shutter I also provide a transverse pivoted slat, K, which, when the shutter is lowered, rests against and closes 65 the slot I.

L is a shaft journaled transversely in one of the pockets or recesses B, near the lower end of the latter, and having a crank or handle, M, by which it may be conveniently manipulated, and carrying a pulley, N, connected by a belt or band, O, with the pulley E upon the roller D.

It will be seen that by operating the shaft L the roller D may be turned so as to raise or 75 lower the shutter, as may be desired.

P P are catches sliding transversely in the lower ends of the sides of the window-casing, and engaging slots Q in the lower or angle slat, J, of the shutter when the latter is lowered. The slides or catches P are provided at their rear ends with handles R, by means of which they may be readily operated.

95
Journalized in the casing C, transversely over the window and rear of the roller D, is another roller, S, having a curtain, T, which extends through a slot, U, in the side of the casing C. The roller S is provided at the end opposite the pulley E on roller D with a pulley, U', connected by a belt or band, V, with a pulley, W, upon a shaft, X, journaled in the lower end of the pocket or recess B, and having a crank or handle, Y, by means of which it may be readily turned so as to raise or lower the curtain.

From the foregoing description, taken in connection with the drawings hereto annexed, the operation and advantages of my invention will be readily understood. By turning the appropriate cranks the curtain and shutter may 100 be raised and lowered, and the shutter, when lowered, may be made securely fast by means of the slides or catches P P.

The construction of the device is simple and

inexpensive, and it may be easily and conveniently manipulated.

I claim as my invention and desire to secure by Letters Patent of the United States—

5. 1. The combination, with a window-frame, constructed with a box or casing at the top, and having recesses or pockets at the sides, said casing and recesses being provided with slots, as set forth, of the roller mounted trans-
10 versely in the said box or casing, and having flexible straps connected by transverse slats, and having at the lower end an angle-plate or slat and at the upper end a pivoted slat, all constructed and arranged to be operated by
15 suitable mechanism, substantially as set forth.

2. The combination, with a rolling window-shutter, constructed and arranged substantially as described, of a slat pivoted to the flexible straps at the upper end of said shutter, and adapted to cover the slot for the passage 20 of said shutter when the latter is lowered, substantially as set forth.

In testimony that I claim the foregoing as my own I have hereto affixed my signature in presence of two witnesses.

JOSEPH WRIGHTSMAN.

Witnesses:

J. C. OBERT,

I. P. CAMPBELL.
